US00D759296S

(12) **United States Design Patent** (10) **Patent No.:** **US D759,296 S**
Abroff et al. (45) **Date of Patent:** **** Jun. 14, 2016**

(54) **HAND-HELD AEROSOL GENERATOR**

(71) Applicant: **Philip Morris Products S.A.**, Neuchatel (CH)

(72) Inventors: **Aaron Abroff**, Acton, MA (US); **Gregor Mittersinker**, Warwick, RI (US); **Laurent Manca**, Grandvaux (CH)

(73) Assignee: **PHILIP MORRIS PRODUCTS S.A.**, Neuchatel (CH)

(**) Term: **14 Years**

(21) Appl. No.: **29/479,202**

(22) Filed: **Jan. 13, 2014**

(56)

(57) **CLAIM**

The ornamental design for a hand-held aerosol generator, as shown and described.

DESCRIPTION

FIG. 1 is a perspective view of an embodiment of a hand-held aerosol generator showing our new design as viewed from the left side of the page;

FIG. 2 is a side elevational view of one side thereof;

FIG. 3 is a top plan view thereof;

FIG. 4 is a side elevational view of the opposite side thereof;

FIG. 5 is a bottom plan view thereof;

FIG. 6 is a front plan view thereof; and,

FIG. 7 is a rear plan view thereof.

1 Claim, 4 Drawing Sheets
